L. F. EDWARDS,
WIRE STRETCHER,
APPLICATION FILED AUG. 16, 1920.

1,374,838.

Patented Apr. 12, 1921.

FIG. 4.

Inventor

Louis F. Edwards

By Wilkinson & Giusta

Attorneys.

UNITED STATES PATENT OFFICE.

LOUIS F. EDWARDS, OF NOBLE, LOUISIANA.

WIRE-STRETCHER.

1,374,838.

Specification of Letters Patent. Patented Apr. 12, 1921.

Application filed August 16, 1920. Serial No. 403,893.

To all whom it may concern:

Be it known that I, LOUIS F. EDWARDS, a citizen of the United States, residing at Noble, in the parish of Sabine and State of Louisiana, have invented certain new and useful Improvements in Wire-Stretchers; and I do hereby declare the following to be a full, clear, and exact description of the invention, such as will enable others skilled 10 in the art to which it appertains to make and use the same.

The present invention relates to improvements in wire stretchers, and has for an object to provide a wire stretcher that is simple in construction and economical of manufacture, at the same time being durable and effective in operation.

A further object is to produce a comparatively light wire stretcher that will 20 enable an effective gripping of the chain usually employed in the operation of devices of this character.

In the accompanying drawings forming a part of this application, and in which 25 similar reference symbols indicate corresponding parts in the several views:

Figure 1 is a fragmentary view with parts shown in elevation of a wire stretcher constructed in accordance with the present invention.

Fig. 2 is a sectional view through the clamping device.

Fig. 3 is a fragmentary plan view of the claws; and

Fig. 4 is a perspective view of one of such claws.

Referring more particularly to the drawings, 1 designates mesh wire forming, for instance, a fence, and 2 designates the usual 40 chain which is affixed to a post or other stationary object.

In accordance with the invention a clamping device is associated with the wire 1, and this clamping device preferably embodies a pair of elongated thin plates 3 and 4 preferably, though not necessarily, of oak, which are clamped upon the end of the wire 1 by means of bolts 5. Straps of iron or other metal 6 and 7 are affixed to the inner 50 faces of the plates to one side the bolt holes so that these straps take up the wear and come directly in contact with the wire.

One of the plates 4 carries an eye-bolt 8 to which to connect the hook 9 of the lever 55 or handle 10. A link 11 engages perforations in the link and handle as shown in

Fig. 1, in order to give the handle or lever a loose pivot point; other links 12 and 13 are connected to eyes in the handle 10 at opposite sides of the pivot point and serve 60 to loosely connect the claw bars 14 and 15.

These claw bars are made preferably of metal and are twisted adjacent their outer ends, as indicated at 16 and 17, and have formed thereon the claws 18 and 19 extending from the twisted portions of the bars. As shown in Fig. 4, the claws may be two in number on each bar, and may be separated by a space 19 which is substantially of the width of the flat side of one of the 70 links of the chain 2, so that the claw may engage the adjacent edge of the next successive link, as indicated in Fig. 2.

In use the plates 3 and 4 are clamped about the end of the mesh wire 1 in the 75 manner indicated in Figs. 2 and 3, and the lever or handle 10 is connected to the clamp by means of the eye 8 and hook 9. The claws are then placed in operative relation with the chain 2 and the handle 10 is worked 80 back and forth so that the claws alternately engage with the chain 2; the chain 2 being connected to a stationary post or the like, will serve as a suitable abutment through which the wire 1 will be stretched. The 85 stretching process is carried on by slow steps so that relatively great tension or stretching effect may be had upon the wire with the application of very little labor.

The peculiar twist given to the bars 14 90 and 15 enables the claws 18 and 19 to be brought in a proper position relatively to the chain 2 without causing complicated structures to be required or a difficult complex apparatus to be used, or any great 95 amount of time or skill to be employed in the making of the same.

The manufacture of the claws from flat bars of metal of a character that may be twisted, gives the opportunity to employ 100 double claws of a width and strong character which effectually engage the chain.

Perforations 20 are provided in the lower end of the handle to which to attach operating cables, if desired, so that the handle may 105 be pulled thereby in opposite directions. The claws are inclined so as to ride over the chain links in moving back to initial position.

It is obvious that those skilled in the art 110 may vary the details of construction and arrangements of parts without departing

from the spirit of my invention, and therefore I do not wish to be limited to such features except as may be required by the claims.

5 I claim:

1. A wire stretcher comprising a lever, and a pair of claws loosely carried by the lever at opposite sides of its fulcrum point, said claws composed of flat bars bent at 10 substantially right angles and provided with double and spaced teeth extending laterally therefrom, substantially as described.
2. A wire fence stretcher comprising a lever, a pair of claw bars loosely pivoted to the lever at opposite sides of its fulcrum, said claw bars being bent through substantially right angles near their outer ends and having spaced apart teeth extending

therefrom, in combination with a chain upon 20 which said teeth are adapted to work, substantially as described.

3. A stretching device of the character described comprising a lever having a fulcrum point intermediate its ends, and a pair 25 of claws connected to said lever at opposite sides of its fulcrum point, said claws comprising each a flat bar having one end thereof bent over at substantially right angles to the plane of the body of the bar and 30 having bent teeth spaced apart by an intermediate slot extending downwardly from said bent portion of the bar, said claws being of different lengths to engage at successive points on a chain or the like, substantially 35 as described.

LOUIS F. EDWARDS.
